[57] CLAIM

The ornamental design for a breast pump, as shown.

DESCRIPTION

FIG. 1 is a perspective view of a breast pump showing our new design;

FIG. 2 is an enlarged top plan view thereof;

FIG. 3 is a side elevational view thereof;

FIG. 4 is a front elevational view thereof, the rear view being a mirror image;

FIG. 5 is a bottom plan view thereof;

FIG. 6 is a side elevational view thereof, the opposite side being a mirror image.

The broken line showing of the breast shield adaptor and the bottle are for illustrative purposes only and form no part of the claimed design.
